UNITED STATES PATENT OFFICE.

HENRY P. CLAUSEN, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

,253,671.

Specification of Letters Patent. Patented Jan. 15, 1918.

Application filed April 12, 1917. Serial No. 161,609.

to all whom it may concern:

Be it known that I, HENRY P. CLAUSEN, a citizen of the United States, residing at Mount Vernon, in the county of Westchester and State of New York, have invented certain new and useful Improvements in Telephone-Exchange Systems, of which the following is a full, clear, concise, and exact description.

This invention relates to telephone exchange systems and more particularly to such systems of the central energy type in which the connection of an operator's telephone set with a calling telephone line is automatically controlled.

The object of this invention is to provide a system of this character by means of which the time of completing connections between phone lines is reduced to a minimum and which more satisfactory service is rendered to the subscribers.

In accordance with this invention, each circuit is equipped with a relay for automatically connecting an operator's telephone set therewith upon connection being made with a calling line. Should a second circuit be connected with a second line the operator's telephone set is connected with the first link circuit, the operator's telephone set is thereupon disconnected from the first and connected with the second circuit, and upon completion of the connection by way of the second link circuit, the operator's telephone set is automatically disconnected therefrom and reconnected with the first link circuit.

This invention is illustrated in the accompanying drawing wherein all apparatus is shown in its normal and unactuated condition.

In the drawing there are shown two telephone lines A and B which extend from subscribers' stations and terminate at a central office. There is also shown located at the central office two link circuits C and D. The link circuits are similarly equipped; for convenience, the same apparatus will be designated by the same reference character, the only distinction made by the addition throughout the designation of the letter C or D to designate a particular link circuit. It will be understood that a large number of telephone lines connect A and B may terminate at this office and that more link circuits

than those shown may also be provided for interconnecting the telephone lines. However, for convenience only the two telephone lines and the two link circuits are shown. It is thought that the nature of this invention is such that it can be best understood from a description of the operation of the system disclosed in the drawing and it will be so described.

Assuming that the subscriber of telephone line A has initiated a call in the usual manner, the operator in answering inserts an answering plug 5 of cord circuit C into line jack 6 of line A. The cut-off relay 7 of line A is thereupon operated over a circuit from battery through answering supervisory lamp 8, normal contact of answering supervisory relay 10, sleeve contacts of the answering plug 5 and line jack 6 and the winding of cut-off relay 7 to ground. The answering supervisory lamp 8 would light over this circuit were it not for the fact that the answering supervisory relay 10 immediately operates, thereby including the resistance 9 in circuit with the lamp 8 and reducing the amount of current through the lamp to such an extent that it is prevented from lighting. Upon the actuation of the answering supervisory relay 10, listening relay 11 is actuated over a circuit from battery through a common resistance 12, normal contact of calling sleeve relay 13, alternate contact of answering supervisory relay 10, winding of listening relay 11, resistance 14, sleeve contacts of the answering plug 5 and the line jack 6 and winding of the cut-off relay 7 to ground. Listening relay 11 in operating, connects the operator's telephone set to the talking strands of the cord circuit C. The common resistance 12 limits the amount of current through the winding of listening relay 11 and resistance 14. The resistance 14 is of such nature that when cold the ohmic resistance thereof is very low, but when heated up as when current is traversing it, the ohmic resistance thereof increases quite rapidly. This resistance 14 may be of the form of a ballast lamp such as is shown and described in Patent No. 854203 to C. D. Enochs. Since the common resistance 12 limits the amount of current through this circuit the increase in resistance of the coil 14 is thereby limited to such an extent that while it will decrease the amount of current through the winding of relay 11 still this

reduction of itself is not sufficient to cause the release of this listening relay.

- Suppose that while the operator's telephone set is connected to this cord circuit 5 C, another line signal appears before the operator at this position. Assume further that the calling subscriber A is not ready to give the number of the line with which connection is desired, the operator may then 10 insert the answering plug 5 of another cord circuit D into the line jack of the other line which has initiated the call. The answering supervisory relay 10-D immediately operates, thereby causing the energization and 15 operation of listening relay 11-D over a circuit from battery through common resistance 12, normal contact of calling sleeve relay 13-D, alternate contact of answering supervisory relay 10-D, winding of listening relay 11-D, resistance 14-D, the sleeve contacts of the answering plug 5-D and the line jack and winding of the cut-off relay of the calling line to ground. The operation of relay 11-D connects the operator's telephone set to the talking strands of 20 the cord circuit D. The circuit including the winding of listening relay 11-D and resistance 14-D established upon the operation of answering supervisory relay 10-D 25 is of comparatively low resistance and is in multiple with the circuit including the winding of relay 11-C and coil 14-C. The coil 14-C is at this time of high ohmic resistance, while the ohmic resistance of the coil 14-D is comparatively low so that the establishment of this second circuit including the winding of relay 11-D and resistance coil 14-D diverts sufficient current from the circuit including the winding of 30 relay 11-C and the coil 14-D, to cause relay 11-C to release its armatures, thereby disconnecting the operator's telephone set from the cord circuit C.
- The operator upon being advised of the 45 number of the line with which the second calling party desires to be connected, inserts the calling plug 15-D into the line jack of the line desired, whereupon the calling sleeve relay 13-D and the cut-off relay of the 50 line operate, and calling supervisory lamp 21-D lights. Relay 13-D, in operating, opens the energizing circuit of relay 11-D, which now releases to disconnect the operator's telephone set from the cord circuit D.
- Immediately upon the opening of this circuit through the winding of relay 11-D, more current is permitted to flow through the winding of relay 11-C, whereupon this relay again attracts its armatures, reconnecting the operator's telephone set to the 55 cord circuit C. Upon the operation of relay 13-D, ringing relay 16-D immediately operates to connect a source of ringing current 17 to the called line. Upon the response of the called party, tripping relay 60 18-D operates, thereby removing the short circuit of a lock-up relay 19, which operates and locks up, short-circuiting relay 16-D, which then releases its armatures, disconnecting ringing current from the called line 70 and establishing the talking circuit. Calling supervisory relay 20-D thereupon operates to extinguish the calling supervisory lamp 21-D.
- Upon the reconnection of the operator's 75 telephone set to the cord circuit C in the manner hereinbefore explained, the operator may converse with the subscriber of line A, and upon learning the number of the line with which connection is desired, inserts 80 the calling plug 15-C into the line jack of line B, it being assumed that this is the line with which connection is desired. Calling sleeve relay 13-C and the cut-off relay of the line B are thereupon operated, and 85 calling supervisory lamp 21-C is lighted. The operation of ringing the call bell at the station on line B is performed in the manner hereinbefore explained. In response to the operation of this call bell subscriber B 90 removes the receiver from the switchhook, whereupon ringing current is removed from line B and the calling supervisory relay 20-C is operated to extinguish the calling 95 supervisory lamp 21-C.
- At the conclusion of the conversation between subscribers A and B and between the subscribers connected together by means of cord circuit D, the restoration to the switchhooks of the receivers causes the release of 100 the supervisory relays of the cord circuits, whereupon the supervisory lamps are lighted to furnish disconnect signals. In response to these disconnect signals the operator removes the plugs from the jacks and 105 the apparatus is returned to its normal condition.
- In order that the disclosed embodiment of this invention may be thoroughly understood, the following more detailed statements regarding the operation of the listening relays of two cord circuits may be of assistance. The common resistance 12 serves to limit the amount of current available in either of the listening relay circuits for the 110 operation of the respective relay. This available current is enough to supply 11-D with sufficient current for drawing up its armatures when its associated coil 14-D is cold. However, when the first cord circuit 120 C is connected with a calling line, and its relay 11 is operated and its resistance coil 14 is hot, the connection of the cord circuit D with another calling line, while the resistance coil 14-D is cold, shunts away 125 from relay 11-C enough current to cause relay 11-C to release its armatures, but even though the cord circuit D remains so connected for a sufficient length of time to permit the heating of resistance coil 14-D 130

to a high degree, the listening relay 11-D will not release its armatures. That is, it will hold its armatures attracted when traversed by this reduced quantity of current. Relay 11-C, will not, while the relay 11-D remains connected in parallel with it, receive sufficient current to cause it to again attract its armatures. As before stated, the common resistance 12 serves to limit the amount of current available for operating the listening relays, and it will be seen that when two relays 11-C and 11-D are connected in parallel, the amount of current in each branch will be less than when only one relay is in circuit.

What is claimed is:

1. A telephone exchange system comprising telephone lines, an operator's telephone set, means responsive to the connection of the link circuit with one of the lines to connect the operator's telephone set therewith, a second link circuit, means actuated upon connection of one end of the second link circuit with another of the lines for causing the disconnection of the operator's telephone set from the first link circuit and the connection thereof with the second link circuit, and means operating upon the connection of the other end of the second link circuit with a third line for causing the disconnection of the operator's telephone set from the second link circuit and the reconnection thereof with the first link circuit.
2. A telephone exchange system comprising telephone lines, an operator's telephone set, a link circuit, a relay energized upon connection of the link circuit with one of the lines to connect the operator's telephone set therewith, a second link circuit, a relay therefor adapted when operated to connect the operator's telephone set therewith, an energizing circuit for the relay completed upon connection of the link circuit with one of the lines, a resistance element having a high positive temperature coefficient in the energizing circuit, a second link circuit, a relay therefor adapted when energized to connect the operator's telephone set with the second link circuit, an energizing circuit therefor completed upon connection of one end of the second link circuit with another of the lines and cooperating with the resistance element to deenergize the relay of the first link circuit, and a relay operating upon connection of the other end of the second link circuit for causing the deenergization of the other relay thereof and the energization of the relay of the first link circuit.
3. A telephone exchange system comprising telephone lines, an operator's telephone set, a link circuit, a relay therefor adapted when operated to connect the operator's telephone set therewith, an operating circuit for the relay established upon connection of the link circuit with one of the lines, a second link circuit, a relay therefor adapted when operated to connect the operator's telephone set therewith, an operating circuit therefor established upon connection of one end of the second link circuit with another of the
4. A telephone exchange system comprising telephone lines, an operator's telephone set, link circuits, a relay in each link circuit adapted when operated to connect the operator's telephone set with the associated link circuit, an operating circuit for each relay completed upon connection of the associated link circuit with a line, the completion of one operating circuit while another is already established causing the diversion of current therefrom to release the relay of the first engaged link circuit, and means responsive to the connection of the link circuit associated with the one operating circuit for causing the diversion of current from the other operating circuit to release the relay thereof and for causing an increased flow of current in the one operating circuit to thereby again operate the relay.
5. A telephone exchange system comprising telephone lines, an operator's telephone set, a link circuit, a relay therefor adapted when energized to connect the operator's telephone set therewith, an energizing circuit for the relay completed upon connection of the link circuit with one of the lines, a resistance element having a high positive temperature coefficient in the energizing circuit, a second link circuit, a relay therefor adapted when energized to connect the operator's telephone set with the second link circuit, an energizing circuit therefor completed upon connection of one end of the second link circuit with another of the lines and cooperating with the resistance element to deenergize the relay of the first link circuit, and a relay operating upon connection of the other end of the second link circuit for causing the deenergization of the other relay thereof and the energization of the relay of the first link circuit.
6. A telephone exchange system comprising telephone lines, a link circuit connected with one of the lines, an operator's telephone set connected with the link circuit, a second link circuit, means responsive to the connection of one end of the second link circuit with another of the lines for disconnecting the operator's telephone set from the first link circuit and for connecting the set with the second link circuit, and an electromagnetic switch operating upon connection of the other end of the second link circuit for causing the disconnection of the operator's telephone set.

ator's telephone set from the second link circuit and the connection thereof with the first link circuit.

7. A telephone exchange system comprising telephone lines, a link circuit connected with one of the lines, an operator's telephone set connected with the link circuit, a second link circuit, a relay in the first link circuit responsive to the connection of one end of the second link circuit with another of the lines for disconnecting the operator's telephone set from the first link circuit, a relay energized upon connection of the second link circuit with that line to connect the operator's telephone set therewith, and a relay actuated upon connection of the other end of the second link circuit with a third line to cause the deenergization of the other relay thereof and the energization of the relay of the first link circuit to again connect the operator's telephone set therewith.

8. A telephone exchange system comprising telephone lines, a link circuit connected with one of the lines, an operator's telephone set connected with the link circuit, a second link circuit, a relay for the second link circuit adapted when energized to connect the operator's telephone set therewith, an energizing circuit for the relay completed upon connection of one end of the second link with another line, a resistance element having a high positive temperature coefficient, a relay deenergized by the coöperation of the resistance element and the energizing circuit upon the completion thereof to disconnect the operator's telephone set from the first link circuit, and means responsive to the connection of the other end of the second link circuit with another line to cause the

disconnection of the operator's telephone set from the second and the reconnection thereof with the first link circuit.

9. A telephone exchange system comprising telephone lines, a link circuit, an operator's telephone set, a resistance element having a high positive temperature coefficient, a relay adapted when energized to connect the operator's telephone set with the link circuit, an energizing circuit for the relay including the resistance element completed upon connection of the link circuit with one of the lines, a second link circuit, a relay therefor adapted when operated to connect the operator's telephone set with the second link circuit, and an operating circuit therefor completed upon connection of the second link circuit with another of the lines and coöperating with the resistance element to deenergize the first relay.

10. A telephone exchange system comprising telephone lines, a link circuit connected with one of the lines, an operator's telephone set connected with the link circuit, a resistance element having a high positive temperature coefficient, a second link circuit, means for disconnecting the operator's telephone set from the first link circuit, a relay adapted when operated to connect the operator's telephone set with the second link circuit, an operating circuit therefor completed upon connection of the second link circuit with another of the lines and coöperating with the resistance element to cause said means to disconnect the operator's telephone set from the first mentioned link circuit.

In witness whereof, I hereunto subscribe my name this 10th day of April A. D., 1917.

HENRY P. CLAUSEN.
